UNITED STATES PATENT OFFICE

JAY R. FOGAL, OF SAN FRANCISCO, CALIFORNIA

FUSE

Application filed May 27, 1931. Serial No. 540,478.

This invention relates to fuses and has particular reference to fuses of the ventilating type embodying means to readily permit visual inspection of the fuse link.

5 The primary object of the present invention is to provide a fuse wherein the fusible element may be readily observed to facilitate inspection.

10 Another object is to provide a fuse of this character which shall present a smooth exterior that is devoid of all projections and which is similar in general appearance to the ordinary fuse.

15 A further object is to provide a fuse of the aforesaid character wherein a sleeve is normally maintained in closed position with respect to an observation aperture and is automatically returned to such position after the sleeve has been moved to observe the fusible element through such aperture.

20 A still further object is to provide a fuse of this character which shall be simple in construction, inexpensive to manufacture and which may be easily operated to permit inspection of the fusible element.

25 With the foregoing and other objects in view, the invention may be stated to consist in the various novel features of construction and arrangement or combination, all of which will be fully described hereinafter and pointed out in the appended claims.

In the drawing accompanying and forming part of this application;

30 Fig. 1 is a side elevation with parts broken away of a fuse constructed in accordance with my invention;

35 Fig. 2 is a longitudinal sectional view taken on the line 2—2 of Fig. 1, and showing the parts in normal position; and

40 Fig. 3 is a similar view but showing the outer sleeve moved to align the observation apertures.

45 Describing the various parts by reference characters, 1 denotes the body portion of the fuse which is made of insulating material and which is preferably cylindrical in shape and provided with diametrically opposed apertures 2. Projecting from each end of the body portion is an internally and externally threaded sleeve 3. A sheet metal

cup shaped member 4 is engaged with the internal threads to define a spiral vent passage 5 which communicates at one end with the interior of the fuse and at the other end with a plurality of apertures 6 formed in an end cap 7. These end caps are threaded on the projecting ends of the sleeves 3 and each end cap is formed with an annular groove 8 which receives a longitudinally slid- 55 able sleeve 9.

60 Interposed between each end cap 7 and cup shaped member 4 is a lock washer 10 of any suitable type which closely embraces a knife blade contact 11 that projects through the end cap. A fusible element 12 interconnects the inner ends of the knife blade contacts and extends through the longitudinal axis of the fuse housing. 65

60 The sleeve 9 is slidably mounted on the cylindrical housing 1, and a spring 14 inter- 70 posed between an end cap 7 and the end of the sleeve serves normally to maintain said sleeve engaged with the opposite end cap. In Fig. 2, I have shown the spring 14 positioned in annular groove 8 in the right hand 75

end cap 7 and the sleeve forced toward the left hand end cap. The sleeve is formed with a pair of diametrically opposed ob- 80 servation apertures 15 which are adapted to align with apertures 2 in the housing when the sleeve 9 is moved to the right, as shown in Fig. 3, thereby permitting the fusible ele- 85

ment 12 to be readily observed. When the sleeve is released, and moves to the left, as shown in Fig. 2, plates 16, which are positioned inside the housing and fastened to the sleeve by pins 17, normally cover the apertures 2. These plates and the sleeve 9 pro- 90

vide a double seal for the apertures 2. A pair of pins 18 which project from housing 1 and engage in longitudinal slots 19 in the sleeve prevent rotation of the sleeve with re- 95

spect to the housing and maintain the apertures 15 and 2 in longitudinal alignment.

When the fusible element 12 melts, due to a short circuit or other overload, the gases generated will escape through vent passages 5 and ports 6 to the atmosphere, thereby avoiding rupture of the housing 1. If at any time it is desired to inspect the fusible ele- 100

ment, it may be easily observed by sliding sleeve 9 longitudinally on the housing to align apertures 15 and 2 and when inspection is completed, the spring 14 will move the sleeve longitudinally to seal apertures 2.

5 The fuse may be easily and quickly disassembled for renewing the fusible element by removing end caps 7 and lock washers 10.

What I claim is:

- 10 1. A fuse of the character set forth comprising a housing, a fusible element disposed within said housing and having end contacts, and a sleeve slidable longitudinally on said housing, said sleeve and housing having apertures adapted to align to permit observation of said fusible element.
- 20 2. A fuse of the character set forth comprising a housing, a fusible element disposed within said housing and having end contacts, a sleeve slidable longitudinally on said housing, said sleeve and housing having apertures adapted to align to permit observation of said fusible element, and resilient means arranged to normally move and hold the sleeve 25 with said apertures out of alignment.
- 30 3. A fuse of the character set forth comprising a housing having a fusible element therein, an end cap disposed at each end of said housing, said end caps each having an annular recess, and a sleeve slidable longitudinally of said housing and engaged in said annular recesses, said sleeve and housing having apertures adapted to align to permit observation of said fusible element.
- 35 4. A fuse of the character set forth comprising a housing having a fusible element therein, an end cap disposed at each end of said housing, said end caps each having an annular recess, a sleeve slidable longitudinally of said housing and engaged in said annular recesses, said sleeve and housing having apertures adapted to align to permit observation of said fusible element, and a resilient element disposed in one of said recesses and adapted to normally move and hold said sleeve with said apertures out of alignment.
- 40 5. A fuse of the character set forth comprising a housing having a fusible element therein, a threaded sleeve projecting from each end of said housing, an end cap engaged with the thread of each sleeve, said end caps each having an annular recess, a sleeve slidable longitudinally of said housing and having the ends thereof engaged in said annular recesses, said sleeve and housing having apertures adapted to align to permit observation of said fusible element, and means for normally moving and holding said sleeve with said apertures out of alignment.
- 45 6. A fuse of the character set forth comprising a housing having a fusible element therein, a sleeve slidable longitudinally on said housing, means for preventing rotation 50 of said sleeve with respect to said housing,

70 said sleeve and housing having apertures adapted to align to permit observation of said fusible element, and means for normally moving and holding said sleeve with said apertures out of alignment.

75 In testimony whereof I affix my signature.

JAY R. FOGAL.
